Patented Aug. 5, 1919.

INVENTOR
WILLIAM PURNHAGEN,
by Arthur C. Eckert ATTORNEY.

UNITED STATES PATENT OFFICE.

WILLIAM PURNHAGEN, OF ST. LOUIS, MISSOURI.

DETACHABLE SHOE ELEMENT.

1,311,914.

Specification of Letters Patent. Patented Aug. 5, 1919.

Application filed March 17, 1919. Serial No. 283,257.

To all whom it may concern:

Be it known that I, WILLIAM PURNHAGEN, a citizen of the United States, and resident of St. Louis, Missouri, have invented certain new and useful Improvements in Detachable Shoe Elements, of which the following is a specification.

This invention relates to improvements in hollow metal detachable heels for shoes, particularly ladies' shoes. Due to the great height of heels worn on ladies' shoes, and due to their conformation, they wear or "run over" in a very short space of time. This means that the heel must be either replaced or the shoe discarded. To replace the heel is an expensive operation.

The object of my invention is to produce a heel that is light in weight, durable, one that permits of resilience when used in walking, one that is quickly detachable by any person, one which need not be taken to a shoemaker to be detached. In attaching the heel to the outsole it becomes necessary to anchor it at more than one point to prevent the rotation or movement of the heel relative to the outsole. It likewise becomes necessary to mark on the outsole the position of the hole to admit the means of joining the heel and outsole to prevent piercing the outsole an unnecessary number of times. This means of marking must be automatic, positive and permit of simplicity in its manufacturing method.

Another and the principal object of my invention is to locate a hole marking means on the heel so that the location of the hole in the insole can be immediately determined on placing the heel on the insole.

Referring to the drawings—

Figure 1 is a fragmental longitudinal elevation of a portion of a shoe with my heel attached.

Fig. 2 is a plan view of my device.

Referring further to the drawings numeral 3 designates a portion of the shoe upper and 4 designates the entire heel; 5 designates a nail block which is positioned as shown in Fig. 1. Numeral 6 designates a hollow internally and externally threaded bolt having the flange 7. The bolt 6 is screwed into the nail block 5 and into the heel 4 at 8. The flange 7 is countersunk into the nail block 5 as shown in Fig. 1. By this means it will be seen that the nail block is detachably secured to the heel by means of the bolt 6. Numeral 9 designates a leather

or rubber or composition block secured to the nail block 5 and hence the heel 4 by means of the nails 10. At the point 11 of the heel 4 is a projection 12 formed integral with the heel 4, which is tapped for a screw, as at 13 Fig. 1. The projection 12 extends upward, as shown in Fig. 1, so that when the heel is placed in contact with the outsole the top of the projection 12 makes an impression in the outsole showing the proper place to pierce the outsole. Numeral 14 designates a small tooth formed integral with the heel for the purpose of piercing the outsole and anchoring that portion of the heel to the outsole; 15 designates a large washer positioned on the inside of the insole having holes pierced through it at the points 16 and 17; 18 and 19 designate two bolts passing through the washer 15 into the heel, as shown in Fig. 1; 20 designates a finish for the inside of the heel of the shoe such as cloth or leather used to cover the washer 15. The advantages of the projection 12 are twofold,—first offers a place into which to screw the bolt 17, and secondly, owing to its height, indicates the place in the outsole for the hole which is to accommodate the bolt 16. This latter feature is particularly important in repair work, in which my heel is put on for the first time by inexperienced men with meager facilities for such work. Without the projection 12, several holes would be pierced in the outsole before the correct position was obtained involving an expenditure of time and material, and sometimes over-running the outsole so that the heel can not be properly fastened.

What I claim and mean to secure by Letters Patent is—

1. In combination with a shoe, a heel, and bolts, said heel secured to said shoe by means of said bolts, and means formed integral with said heel for locating the bolt holes of said shoe through which one of said securing bolts is positioned, said means so positioned relative to the plane of contact between said heel and said shoe that the positioning of said heel on said shoe will indicate the position of said bolt securing means on said shoe by indicating thereon by an indentation the position of said bolt holding means.

2. In combination with a shoe, a hollow heel, a nail block, a hollow internally and externally threaded bolt and block, said block secured to said nail block and said

block secured to said heel by a threaded engagement of said hollow bolt with said heel and said block, and a bolt securing means formed integral with said heel, said means so positioned relative to the plane of contact between said heel and said shoe that the positioning of said heel on said shoe will indicate the position of said bolt securing means on said shoe by indicating thereon by

an indentation the position of said bolt holding means.

In testimony whereof, I have signed my name to this specification in presence of two subscribing witnesses.

WILLIAM PURNHAGEN.

Witnesses:
